UNITED STATES PATENT OFFICE.

JAMES WARD HOLLAND, OF NEWARK, NEW JERSEY.

WASHBOARD.

1,169,037.

Specification of Letters Patent. Patented Jan. 18, 1916.

Application filed October 12, 1915. Serial No. 55,469.

To all whom it may concern:

Be it known that I, JAMES W. HOLLAND, a citizen of the United States, and a resident of Newark, in the county of Essex and State 5 of New Jersey, have invented a new and Improved Washboard, of which the following is a full, clear, and exact description.

My invention relates to a washboard provided with yielding means against which the 10 person using the board may bear so that the said means will yield to the pressure of a washwoman instead of offering an unyielding resistance which is liable to result in injury.

15 Objects of my invention are to provide a yielding means for the indicated purpose adapted to be applied to an ordinary washboard; to provide an attachment of the indicated character having increased efficiency 20 and to provide a simple, strong and durable construction which will be unfailing in performing its function.

The invention will be particularly explained in the specific description following.

25 Reference is to be had to the accompanying drawings forming a part of this specification in which similar reference characters indicate corresponding parts in all the views.

30 Figure 1 is a front elevation of a washboard equipped with my invention; and Fig. 2 is a cross section on the line 2—2, Fig. 1.

In carrying out my invention in accordance with the illustrated example, the washboard 35 may be of the usual form presenting side bars 10, the rubbing board 11, top cross bar 12, and lower cross bar 13, the sides being extended as at 10^a below the cross bar 13 to provide legs in the ordinary manner.

40 My improved attachment comprises a cross bar 14, disposed above the fixed cross bar 12 of the washboard and separate from the latter. Extending downwardly from the cross bar 14 at each side is a guide rod

45 15. The rods 15, have guided movement in suitable guides 16, here shown as eyes on each side 10, of the washboard. In practice the guides 16 may consist of ordinary screw-eyes. At the lower ends the guide rods 15

50 are offset and given the form of loops 17,

which loosely embrace the legs 10^a, so as to slide freely thereon. Beneath the offset loops 17, compression springs 18, are provided on the legs 10^a, extending about the latter. The springs 18, may be sustained 55 in any suitable manner; in the present instance pins 19 are provided in the legs 10^a, beneath said springs.

With the washboard equipped with my attachment, it will be clear that a person in 60 rubbing clothes on the washboard, will be protected against the unyielding resistance of the fixed elements of the board, because the contact will be with the cross bar 14, which will yield to the pressure, the shock 65 being transmitted to the springs and absorbed by the latter.

It will be seen that the form of the elements entering into my attachment is such as to permit of their ready application to 70 ordinary washboards. Moreover the construction and arrangement of the parts are such as to insure strength and durability, and to require no great degree of care on the part of those using or handling the wash- 75 board, equipped with the invention.

Having thus described my invention I claim as new, and desire to secure by Letters Patent:

1. A washboard having yielding means at 80 the top thereof to receive the pressure of a person bearing against the board in washing, said means including a cross bar above the top of the board and movable relatively thereto, coil springs supported on and embracing the legs of the washboard below the rubbing surface thereof, and lateral members extending from the said cross bar and engaged by said springs to yieldingly sustain the cross bar in position. 90

2. An attachment for application to a washboard to afford a yielding bearing member against which the person using the board may exert pressure, said attachment comprising a cross bar adapted to be disposed above the washboard, guide rods extending forwardly from the said cross bar and of a length to position their lower ends at the legs of the board, means adapted to be secured to a washboard at the side and af- 100

fording guides for the said rods, and springs adapted to be positioned on the legs of a washboard, the said guide rods having members to bear against said springs; together with means to secure the springs in position on the legs of the board.

In testimony whereof I have signed my

name to this specification in the presence of two subscribing witnesses.

JAMES WARD HOLLAND.
